STEAM GENERATOR APPARATUS

Hans Conrad Egloff, Winterthur, Switzerland, assignor to Sulzer Freres Société Anonyme, Winterthur, Switzerland

Application September 22, 1936, Serial No. 101,910
In Switzerland October 12, 1935

2 Claims. (Cl. 122—459)

This invention relates to apparatus for the separation of impurities from a fluid in tubular, continuous-flow steam generators comprising at least two series-connected separators and has for 5 its object the provision of an improved apparatus of this character. More particularly, the invention aims to provide an improved combination of steam generator apparatus comprising a cooling device connected between two separators.

10 It has been proposed heretofore to provide the tubular system of continuous-flow steam generators with a separating device for removing feedwater impurities from the steam. Separators have been connected in the system where impurities such as salts were still in solution or where 15 the steam was slightly superheated. There are disadvantages inherent in such apparatus due to incomplete separation of enriched salt solution from the steam, or to the accumulation of salt 20 incrustations in the tubing. It has also been proposed to employ a plurality of separators in the tube assembly of a single tube steam generator, but in such apparatus, solid entrained particles can only be removed with great difficulty and 25 incrustations on the tube walls, between the separators, cannot be dissolved, in certain instances, due to the separation of water from the steam in the first separator.

It is an object of this invention to substantially 30 overcome the aforementioned disadvantages and to provide apparatus from which crusts clinging to the tube walls, between the separators, may be removed, and in which impurities entrained in the steam can be separated at a suitable point 35 in the system by means of condensate.

The invention will be better understood if reference is made to the accompanying drawings, taken in conjunction with the following description, in which

40 Fig. 1 is a diagrammatic illustration (with the tubing straightened out) of a single-tube steam generator in accordance with the invention;

Fig. 2 shows the temperature conditions prevailing in the tubing shown in Fig. 1;

45 Fig. 3 illustrates another adaptation of apparatus in accordance with the invention, and

Figs. 4 and 5 show details of structure in accordance with the invention.

50 Into one end of the tubing 1 (Fig. 1) liquid is fed through supply conduit 2 and superheated steam is taken off at the other end and carried by the delivery conduit 3 to the place of consumption. At point 4 in the tube system the liquid begins to evaporate. At point 5 the first sepa-

rator 6 is connected to the tubing 1 and just beyond, the second separator 8 is connected at point 7. A sludge draw-off is connected to the conduit 9, and to the second separator a sludge draw-off conduit 10 is connected to the separator. The amounts of the sludge thus drawn off can be regulated by means of valves 11 and 31, respectively.

Arranged between the two separators 6 and 8 is a device 27 by means of which the steam flowing from point 5 to point 7 is cooled. The cooling device can, for example, constitute the heating surface of an intermediate superheater, or reheater into which steam to be superheated (for example steam at a lower pressure) is fed through conduit 28. The steam flows from the superheater to the place of consumption through conduit 29. The wet low-pressure steam is thus superheated and the superheated high-pressure steam is saturated.

Inserted on one side of the intermediate superheater is the temperature-responsive device 30 which acts upon the element 11 in the sludge line 9 in such a way that the steam issuing from the separator 6 has its condition maintained about constant. For practical purposes it is advisable to draw off sludge-carrying liquid continuously from the separator 8. For this purpose the valved element 31 in the sludge draw-off line 10 is given the form of a nozzle (32, Fig. 4). The cross-sectional area of the nozzle which controls the amount of liquid passing therethrough is such that the amount of liquid separated in the separator 8 is provided an opportunity to flow therethrough. If for once a smaller amount of sludge should form, in that case steam would blow off together with liquid. But since the weight of the steam that can flow through a nozzle amounts to only one tenth of that of the water flowing therethrough, the loss thus occasioned becomes immaterial.

Fig. 2 shows the temperatures of the fluid medium in the pipe system of Fig. 1. The various points indicated by numerals 2, 4, 5, 7 and 3, correspond to points indicated on the pipe shown in Fig. 1. As shown on the graph, the temperature T of the fluid medium increases from the admission end of the tubing 2 up to the point 4 where it reaches the vaporization temperature T_v . Because of the pressure drop due to friction in the tubular system the vaporization temperature T_v is apt to drop slightly up to point 5. Ahead of the separator 8, the temperature begins to rise in the superheating zone and drops again to the

50 55 60 65 70 75 80 85 90 95 100

vaporization temperature T_v due to cooling effects and then rises ahead of point 7 finally to the utilization temperature T_u at point 3.

One consequence of cooling the steam between 5 the separators is that its condition reverts again to the saturation range. During this retrogradation, part of the steam condenses. The fine solid particles suspended in the steam then act as condensation nuclei and are made heavier by 10 the condensate. The particles having thus been made heavier can then be precipitated in the second separator 8 and abstracted from the steam generator together with entrainment liquid.

In the steam generator shown in Fig. 3 the 15 tubular system is heated by means of a firing installation 13. The liquid fed into the tubular system enters it through conduit 2, and the steam is led through conduit 3 to the places of utilization. A first separator 6 is arranged at that point 20 of the tubular system where about 10% of the total amount of the working medium is still liquid. A second separator 8 is mounted in such a manner as to be located in the rear of the place where the impurities precipitating from the liquid residue 25 due of the first separator remain adhering to the tube walls.

Inserted between the first separator 6 and the second separator 8 is a temperature-responsive apparatus 15, and on this side of the exit end of 30 the tubing another temperature-responsive apparatus 16. The temperature-actuated device 15 acts by means of conduit 17 upon the control element 11 in the sludge draw-off pipe 9 in such a way that the steam arriving in the separator 8 has 35 already absorbed one third of the superheating heat. A residue amounting to about 3% of the liquid (figured on the total amount of the working medium) then still remains behind in the steam passing into part 18 of the generator tubing. The feed impurities that remain adhering 40 in part 18 of the tubular system can, by increasing from time to time the amount of feed water, be impelled forwardly into the separator in which they are separated from the steam and carried off through the condenser trap 19. The amount 45 of liquid to be fed into the system can be increased by lessening at predetermined intervals the amount of sludge to be taken out of the separator 6 or interrupting the sludging-off altogether.

50 The temperature-responsive apparatus 16 actuates via conduit 21 an element 22 in the conduit 23. The element 22 is opened whenever the temperature-actuated apparatus 16 indicates too low a temperature, in order thus to prevent liquid 55 from being entrained to the places of consumption. An element 24 in the conduit 25 acts upon the means provided for feeding additional liquid working medium for the purpose of regulating the temperature of the steam. The additional 60 liquid must be purified to such an extent that

in part 26 of the tubing connected with the separator 8 deposits of impurities no longer form.

At point 35 additional ("make-up") liquid is admitted through conduit 33, which cools the already superheated steam back again to the 5 vaporization temperature. During this cooling stage the condensing steam attaches itself to the solid impurities acting in the manner of condensation nuclei, so as to increase the weight of said impurities and to permit of separating them 10 from the steam in the next separator 8.

In the apparatus illustrated in Fig. 5, the sludging-off element 11 in the conduit is acted upon by a thermostat 34 arranged ahead of the point of admission 35 of the cooling liquid fed 15 in through conduit 33. The condition of the steam at the point of installation of the temperature-responsive apparatus 34 is thus maintained substantially constant.

I claim:

1. Apparatus for the separation of feed-water impurities from steam in tubular, continuous-flow steam generators which comprises a tube into which feed-water is passed at one place and superheated steam removed at another place, a 25 separator connected to the tube at a point where steam and water flows through the tube, said separator being provided with sludge draw-off conduit whereby sludge may be removed from the separator, a valve in said conduit controlling 30 the discharge of sludge-carrying fluid through said conduit, a second separator connected to the tube beyond the first mentioned separator in the direction of steam flow, means for heating the steam in the tube after it has passed through 35 the second separator, a reheat for low pressure steam connected to the tube between the separators, said reheat and tube being located and arranged to permit heating of the tube between the first mentioned separator and the reheat 40 and to prevent appreciable heating of the tube between the reheat and the second separator whereby the steam may be heated after passing the first mentioned separator, cooled in the reheat and passed to the second separator without appreciable vaporization, and means for drawing off sludge-carrying fluid from said second 45 separator.

2. A tubular continuous-flow steam generator which comprises a reheat connected to the tube at a point where the steam is superheated, said reheat being provided with means for passing low-pressure steam in heat exchange relation with the superheated steam, thereby cooling the steam and effecting a precipitation of condensate, 55 and a separator connected to the tube at a point beyond the reheat in the direction of steam flow for removing condensate together with entrained or suspended impurities from the steam.
